UNITED STATES PATENT OFFICE.

JULIUS LAMBERT, OF HOBOKEN, NEW JERSEY.

DESIGN FOR A WAIST-BELT.

SPECIFICATION forming part of Design No. 20,571, dated March 10, 1891.

Application filed January 29, 1891. Serial No. 379,582. Term of patent 14 years.

To all whom it may concern:

Be it known that I, JULIUS LAMBERT, a citizen of the United States, residing at Hoboken, in the county of Hudson and State of New Jersey, have invented and produced a new and original Design for Waist-Belts, of which the following is a specification.

This design has for its object to provide a novel, characteristic, and ornamental waist-belt; and the leading features thereof consist in a flat waist-belt formed in its upper edge with an approximately V-shaped notch and on its lower edge with an approximately V-shaped extension and divergent arms having curved outer edges extending across the face of the flat belt and conforming at the upper ends to the approximately V-shaped notch in the top edge of the belt.

The design is illustrated by the accompanying drawing, in which the figure is a perspective view of the waist-belt.

In the drawing, the letter A indicates a flat waist-belt formed in its upper edge with the approximately V-shaped notch *a* and on its lower edge with the approximately V-shaped extension *a'*. The pendent and divergent arms *b* are provided with curved outer edges *b'* and extend across the face of the flat belt, while their upper ends conform to the approximately V-shaped notch in the top edge of the belt.

What I claim is—

The design for a waist-belt, as herein shown and described.

In testimonay whereof I have hereunto set my hand in the presence of two subscribing witnesses.

JULIUS LAMBERT.
